Inventor:

Josiah H. Kidder

UNITED STATES PATENT OFFICE.

JOSIAH H. KIDDER, OF PUEBLO, COLORADO.

HYDRANT-COCK.

SPECIFICATION forming part of Letters Patent No. 707,119, dated August 19, 1902.

Application filed December 27, 1900. Serial No. 41,297. (No model.)

To all whom it may concern:

Be it known that I, JOSIAH H. KIDDER, a citizen of the United States, residing at Pueblo, Pueblo county, in the State of Colorado, 5 have invented a new and useful Hydrant-Cock, of which the following is a specification.

My invention relates to improvements in a hydrant-cock in which a hydrant-cock with a double elbow is made to connect with the 10 supply-pipe and discharge-pipe at bottom of hydrant-box.

The objects of my improvements are, first, to provide a hydrant-cock with a double elbow that may be fitted, placed, or replaced 15 from top of ground, working through the hydrant-box, without the necessity of digging out the hydrant; second, to provide a key or wrench by which the hydrant-cock may be placed and screwed upon the supply-pipe or 20 may be screwed from the supply-pipe and removed from the hydrant. I attain these objects by the mechanism illustrated in the accompanying drawings, in which—

Figure 1 is a side elevation of the hydrant-cock connected up to the supply and discharge and in position in the hydrant-box, the latter being in vertical section. Fig. 2 is a side elevation of the hydrant-cock with the connections made thereto. Fig. 3 is an end 25 view of the hydrant-cock detached, and Fig. 4 is a side view of a part of the hydrant-cock key-head.

To put my invention into practice, I construct the hydrant-cock E with grooves d d, 30 forming a shoulder b. This hydrant-cock is entirely arranged in the hydrant-box D and

has the supply-pipe A and discharge-pipe B connected thereto. A hydrant-cock key-head is employed and has a slot a in its lower end and is provided at this lower end with ribs c c, which are adapted to engage in the grooves d d when the head b is engaged in the slot a. 40

In connecting or disconnecting the hydrant-cock the slot a in the key-head is slipped over the shoulder or oblong bur b on the hydrant-cock, the ribs c c of the key-head fitting in the grooves d d under the shoulder or bur b, thus holding the hydrant-cock while fitting or removing the same. Thus the key may be fitted from the surface, working through the hydrant-box, and the hydrant-cock screwed from the supply-pipe, or when putting on the hydrant-cock is fitted in key, as above, lowered to bottom, and screwed upon the supply-pipe at bottom of hydrant. 55

I am aware that prior to my invention hydrant-cocks with double elbows have been made. I therefore do not claim such invention, broadly; but

What I do claim as my invention, and desire to secure by Letters Patent, is—

The double-elbow hydrant-cock herein described, provided with the shoulder b combined with the key provided with the slot a and the ribs c c, as set forth. 65

In testimony whereof I have hereunto signed my name to this specification in the presence of two witnesses.

JOSIAH H. KIDDER.
